UNITED STATES PATENT OFFICE.

LEWIS P. HALLADAY, OF MARION, INDIANA.

DESIGN FOR A CRANK-SHAFT SLEEVE.

SPECIFICATION forming part of Design No. 31,492, dated September 5, 1899.

Application filed October 20, 1898. Serial No. 694,141. Term of patent 7 years.

To all whom it may concern:

Be it known that I, LEWIS P. HALLADAY, a citizen of the United States, residing at Marion, in the county of Grant and State of Indiana, have invented and produced a certain new and useful Design for Crank - Shaft Sleeves, of which the following is a specification.

My invention relates to designs for crank-shaft sleeves and is illustrated in the accompanying drawings, wherein—

Figure 1 is a view showing a device embodying my design. Fig. 2 is a section on line 22, Fig. 1.

Like letters refer to like parts throughout both figures.

My design herein illustrated consists of the

sleeve or part A, provided at its ends with the ball cups or retainers B. The sleeve A is provided with the slot A', which extends the entire length of said sleeve, as shown. The crank-shaft is mounted in the device when in use.

The essential feature of my invention is the sleeve A, provided with the slot A' and the ball cups or retainers B.

I claim—

The design for a crank-shaft sleeve substantially as herein shown and described.

LEWIS P. HALLADAY.
